COAL BURNER

Alexandre Adrianoff, Brussels, Belgium

Application February 26, 1935, Serial No. 8,294
In Belgium August 17, 1934

5 Claims. (Cl. 122—368)

My present invention relates to improvements in coal burners used, namely, for the combustion of very small size coals.

It more particularly concerns burners in which the fuel falls, from a hopper, on an inclined surface and which comprises a device for the insufflation of air into the fuel.

In the burners of this type, the walls of the combustion chamber are generally surrounded by a water chamber which serves to cool them down and to recover the heat arising from the combustion of the coal. The heating of the cooling water is however much more intense in the close vicinity of places where the combustion proceeds and namely in places where curvatures resulting in narrow passages occur in the walls of the combustion chamber to form the slide surfaces, the blow-ports, etc. The water circulation does not operate therefore so freely at these places, which may cause an excessive rise in temperature of the water.

On the other hand, in existing burners, the insufflation of air into the fuel is generally soon hindered by the formation of clinkers.

The present invention has for its object to avoid these drawbacks and to provide a burner particularly simple in construction, enabling, namely, to avoid a retardation of the combustion when clinkers are formed.

With this object in view, my invention essentially consists in the special arrangements and combinations of parts hereinafter fully described and pointed out in the appended claims.

The annexed drawing shows by way of example a form of embodiment of a coal burner constructed according to the invention.

Figure 1 is a vertical cross section through a plane perpendicular to the axis of the coal burner.

Figure 2 is a vertical cross section through a plane according to the axis of the coal burner.

In these figures, 1 designates the combustion chamber which is preferably formed by a cylindrical wall 2, surrounded by a water jacket 3, comprised between the wall 2 and an outside wall 4.

According to the invention, the wall 2 forms on a portion of its length, an inclined ledge 5 laterally disposed and leading by a tongue-shaped curve 6 to a surface 7 which through the curve 8 joins again the inner cylindrical wall 2, thus providing, on the one hand, a water chamber between the surface 7 and the inclined ledge 5, and on the other a free space between the surface 7 and the bottom of the cylindrical wall 2.

Above the inclined ledge 5 is an opening 9 laterally disposed and connected to a hopper adapted to receive the coal, whilst under the surface 7 is a nozzle 10 for the injection of air under pressure.

The coal, which falls through the opening 9, forms inside the combustion chamber 1 a heap with a main slope 11 whilst, from the end of the tongue 6 is formed another slope 12 in the free space 13 in which air under pressure is blown.

The combustion chamber 1 is closed in front by a door 14, fixed on a ring 15 connected to the cylinder 2, and is at the back in communication with the inside of a hearth or of a central heating boiler, for instance, through a conduit or duct 16 formed by a ring 17 which is connected to the cylinder 2.

The rings 15 and 17 are hollow and form annular ducts 18 and 19 which are connected to the air blowing device and through which passes air 20 which can enter into the combustion chamber 1, through openings 20 and 21 provided above the front slope 22 and the back slope 23 of the heap of coal, which latter falls in through the opening 9.

The coal burner thus constructed operates as follows:

The fuel falls by gravity through the opening 9, partly fills the combustion chamber 1 forming therein a heap with a top slope 11, a front slope 22 and a back slope 23. The fuel lies on the bottom of the wall 2 and forms further in the free space 13 a supplementary slope 12 which closes this space 13. In the latter the nozzle 10 for the insufflation of air opens. It follows that the air thus blown in completely fills the space 13 and is introduced into the fuel through the slope 12.

In fact the air under pressure will tend to follow preferably the line of least resistance which runs along the bottom wall of the cylinder 2. It follows that the clinkers which form at the lower end of the inclined ledge 5 do not constitute a bar to the passing of the air. On the contrary, clinkers formed at the lower end of the inclined ledge 5 facilitate to some extent the passing of the air through the mass of fuel, by the progressive diminution of the thickness of the heap.

On the other hand, the end of the nozzle is not in contact, as is the case in most existing burners, with the ignited mass of fuel, and the bottom edge of the inclined ledge 5 is outside the zone of combustion having the highest temperatures, since the combustion of the coal takes place

mainly along the slope 12 and along the lower portion of the wall of the cylinder 2. Moreover, the bottom part of the inclined ledge 5 is well cooled down by the water which circulates easily in the chamber formed by this incline and the surface 7.

It should be noted that when the coal is ignited, it is possible to obtain a slow combustion by interrupting the mechanical air insufflation, 10 without fear of complete extinction, as the slow combustion can take place with an ordinary draft; the heated air contained in the rings 15 and 17 enables to relight the distillation gases when the air insufflation device is again brought 15 into action.

What I claim is:

1. In a coal burner in combination with a combustion chamber provided with a water jacket, an inclined ledge laterally disposed in the said chamber and leading by a tongue-shaped curve to a surface which through another curve joins again the inner wall of the combustion chamber, whereby a water chamber is obtained between the said surface and the said inclined 20 ledge and a free space is formed under the said surface between the latter and the bottom of the said wall, a slope of coal being formed in the said free space, and means whereby air is blown into the said free space above the said slope of coal.

2. In a coal burner in combination with a combustion chamber provided with a water jacket, an inclined ledge laterally disposed in the said chamber and leading by a tongue-shaped curve to a surface which through another curve joins again the inner wall of the combustion chamber, whereby a water chamber is obtained between the said surface and the said inclined ledge, the distance between the said surface and the bottom of the combustion chamber being such that a slope of coal is formed in the said space, and means whereby air is blown into the said space.

3. In a coal burner in combination with a combustion chamber provided with a water jacket, an inclined ledge laterally disposed in the said chamber and leading by a tongue-shaped curve to a surface which through another curve

joins again the inner wall of the combustion chamber, whereby a water chamber is obtained between the said surface and the said inclined ledge, the distance between the said surface and the bottom of the combustion chamber being such that a slope of coal is formed into the said space, and means whereby air is blown into the said space, an opening for the introduction of the coal being arranged laterally in the said combustion chamber in such a manner that an upper slope, a front slope and a back slope are formed. 5

4. In a coal burner in combination with a combustion chamber provided with a water jacket, an inclined ledge laterally disposed in the said chamber and leading by a tongue-shaped curve to a surface which through another curve joins again the inner wall of the combustion chamber, whereby a water chamber is obtained between the said surface and the said inclined ledge, the distance between the said surface and the bottom of the combustion chamber being such that a slope of coal is formed into the said space, and means whereby air is blown into the said space, an opening for the introduction of the coal being arranged laterally in the said combustion chamber in such a manner that an upper slope, a front slope and a back slope are formed. 10

4. In a coal burner in combination with a combustion chamber provided with a water jacket, an inclined ledge laterally disposed in the said chamber and leading by a tongue-shaped curve to a surface which through another curve joins again the inner wall of the combustion chamber, whereby a water chamber is obtained between the said surface and the said inclined ledge, the distance between the said surface and the bottom of the combustion chamber being such that a slope of coal is formed into the said space, and means whereby air is blown into the said space, an opening for the introduction of the coal being arranged laterally in the said combustion chamber in such a manner that an upper slope, a front slope and a back slope are formed. 15

5. In a coal burner in combination with a combustion chamber provided with a water jacket, an inclined ledge laterally disposed in the said chamber and leading by a tongue-shaped curve to a surface which through another curve joins again the inner wall of the combustion chamber, whereby a water chamber is obtained between the said surface and the said inclined ledge forming together a tongue and a free space 20 under the said surface of the tongue between the latter and the bottom of the said wall, whereby a slope of coal is formed in the said free space, and means whereby air is blown into the said free space and is projected under the face of the 25 tongue and is then dispersed before passing through the heap of coal. 30
